(No Model.)

H. COMSTOCK.
GUN LOCK.

No. 414,796.

Patented Nov. 12, 1889.

UNITED STATES PATENT OFFICE.

HARRY COMSTOCK, OF FULTON, NEW YORK, ASSIGNOR TO THE HUNTER & COMSTOCK ARMS COMPANY, OF SAME PLACE.

GUN-LOCK.

SPECIFICATION forming part of Letters Patent No. 414,796, dated November 12, 1889.

Application filed June 12, 1889. Serial No. 313,982. (No model.)

To all whom it may concern:

Be it known that I, HARRY COMSTOCK, a citizen of the United States, residing at Fulton, in the county of Oswego and State of New York, have invented new and useful 5 Improvements in Gun-Locks, of which the following is a specification.

My invention relates to that class of firearms commonly known as "hammer guns," and the purpose thereof is to provide a gun-lock in which the hammers are actuated by coiled springs, the parts being so constructed and combined as to secure a perfect rebound of the hammers, while a substantial equilibrium of spring-pressure is obtained at every 15 angle assumed by the tumblers.

It is my purpose, also, to simplify and improve the construction of the lock by reducing the number of parts and so forming and 20 combining the same together that the guide-spindles supporting the springs shall form an inner bearing or guide for the tumblers and retain the hammers firmly in place.

The invention consists in the novel features of construction and new combinations of parts hereinafter fully set forth, and then definitely pointed out in the claims following this specification, reference being had to the accompanying drawings, in which—

30 Figure 1 is a side elevation of a gun-lock embodying my invention, showing the hammer cocked. Fig. 2 is a sectional elevation, the hammer being shown in dotted lines. Fig. 3 is a plan view of the lock. Fig. 4 is a 35 transverse vertical section taken upon the line $x-x$, Fig. 2, the hammers being removed. Fig. 5 is a detail perspective showing the tumblers, the journal-pin, and one of the shoes detached. Fig. 6 is a side elevation 40 of one of the guide-spindles, the shoe, the tumbler, and sear, showing the position of the parts at the full stroke of the hammer.

In the said drawings, the reference-numeral 1 designates the frame of the lock, consisting 45 of a base-plate having substantially the same construction now in use. From this plate rises a central longitudinal plate 2, extending nearly to the forward end of the base-plate, and upon each side of the latter at or 50 near its forward extremity is a lug or plate

3 parallel with and rising nearly to the height of the central plate.

The numeral 4 denotes the hammers, each of which is fitted upon the square of its tumbler 5. Said tumblers each consist of a substantially-segmental metallic block 6, having a cylindrical bearing 7, which lies in a seat 8, cut in the rearward edge of the lug-plate 3, the block 6 being of such thickness as to fit loosely and move freely between the latter 60 and the central plate 2. Upon the block 6 is formed the actuating-tumbler, consisting of a slotted block or of two parallel plates 9, which lie adjacent to the central plate 2 and lug-plate 3, respectively, in which position 65 they straddle the spindle 18. In the segmental block 6 are formed notches 10, with which the sear 12 engages at half-cock and full-cock, respectively. The sear is formed or mounted upon a sear-plate 13 and supported by a sear-screw 14, passing through the central plate 2. A bifurcated sear-spring 15 is attached to the base-plate in rear of the central plate 2, its arms lying upon opposite 70 sides thereof and resting upon the rearward ends of the sears. Directly behind the rearward end of the central longitudinal plate 2 is arranged a T-plate 16, secured to the base-plate by a screw 17, and through the extremities of the horizontal arms of said T-plate are 75 inserted spindles 18, having threaded ends which engage a cross-head 19, lying against the forward end of the central plate 2. Upon these spindles are mounted shoes 20, having openings 21, which are expanded slightly 80 upon the forward faces of the shoes to form oval or elongated apertures receiving the spindles, the elongation being in a plane parallel with the central plate 2, whereby a limited rocking movement of the shoe in a plane 85 parallel with the central plate is permitted as it moves backward and forward upon the spindle. The shoes are impelled by strong spiral springs 22, coiled upon the guide-spindles 18. The face of each shoe adjacent to 90 the actuating-tumbler 9 is concaved slightly, and the rearward edges of the tumbler 9 are sufficiently convex to fit therein with substantial accuracy when the hammer is thrown down. The upper rearward angle 9^a of the 100

actuating tumbler-plates 9 is rounded off to enable it to ride smoothly over the concave face of the shoe. The tumblers are supported by a journal-pin 23, which projects somewhat beyond the outer faces of the hammers and receives nuts 24, by which the hammers are held on the square of the tumblers and the pin prevented from coming out. As the hammer is thrown back 10 the tumbler-plates 9, which straddle the spindle 18, are drawn toward the rear, the convex edges of the same passing off the concave face of the shoe and the rounded angle 9^a of the tumbler riding thereon. As this engagement is made the shoe is not only retracted, but it is rocked or deflected, first at the upper end and then at the lower, whereby, as the point of engagement between the shoe and the tumbler moves from above the axis 20 of the spindle to a plane below the same, an equilibrium of pressure is obtained at every point. At the point where the sear engages the full-cock notch the rounded angle 9^a of the tumbler 9 lies substantially in the same 25 plane with the axis of the spindle 18 or against the middle part of the shoe. As the trigger is pulled, the spring 22 projects the shoe forward, and as the point of contact with the tumbler moves rapidly upward the shoe 30 is inclined somewhat, its upper end lying somewhat nearer the rear end of the spindle than its lower end. As the hammer delivers its blow the shoe recovers its normal position for an instant until the recoil or rebound of 35 the hammer rocks the upper end of the shoe toward the rear, which it is able to do by reason of the fact that the recoil is resisted at the instant only by the lower end of the shoe, at which point the leverage is at its maximum. 40 As the recoil or rebound takes place the shoe recovers its normal position and its concave face seats upon the convex rear edges of the tumbler-plates, bringing the hammer to the point where the sear drops into the half-cock 45 notch as the trigger is released. As the hammer is projected forward by its momentum the lower angle of the shoe lies in the angle or pocket 25 between the segmental block 6 and the tumbler 9, and the shoe is rocked and 50 the spring very slightly compressed thereby, the natural tendency of the shoe to seat upon the convex edges of the tumbler 9 and restore an equilibrium or equality of tension above and below the spindle causing the hammer 55 to rebound without materially impairing the force of the blow.

What I claim is—

1. In a gun-lock, the combination of a journal-pin carrying a tumbler-block provided 60 with an upwardly-projecting tumbler, a sear engaging the tumbler-block, a sear-releasing trigger, a hammer rigidly attached to the tumbler-block below the tumbler, and a spiral spring operating on the tumbler of the tumbler-block, substantially as described.

2. In a gun-lock, the combination of a journal-pin carrying a tumbler-block provided with an upwardly-projecting tumbler, a hammer rigidly attached to the tumbler-block below the tumbler, a spindle, and a spiral 70 spring compressed on the spindle by the rearward movement of the tumbler when the hammer is cocked, substantially as described.

3. In a gun-lock, the combination of a tumbler-block having a tumbler, a hammer rigidly attached to the tumbler-block, a spindle provided with a spiral spring, and a shoe 75 acted on by the spring, sliding on the spindle, and pressing on the tumbler, substantially as described.

4. In a gun-lock, the combination, with a hammer mounted upon the square of a slotted or two-part tumbler, of a spiral spring coiled upon a spindle which is straddled by said tumbler, and a shoe carried by and sliding 85 upon the spindle between the tumbler and the spring, substantially as described.

5. In a gun-lock, the combination, with a hammer mounted on the square of a slotted or two-part tumbler having convex rear edges, 90 of a shoe having a concave face engaging the edges of said tumblers and a spiral spring impelling the shoe and coiled upon a spindle straddled by the tumbler, said shoe being provided with an aperture which is flared or 95 expanded upon opposite sides, substantially as described.

6. In a gun-lock, the combination, with a base-plate having a central longitudinal plate and provided with lug-plates parallel 100 with said central plate, of tumblers lying between the central plate and the lug-plates and having bearings lying in seats in the edges of said lug-plates, a journal-pin passing through both tumblers and resting in a 105 seat in the central plate, shoes mounted upon spindles which are straddled by the tumblers, and spiral springs coiled upon the spindles and impelling said shoes, substantially as described.

7. In a gun-lock, the combination, with a base-plate having a central longitudinal plate, of tumblers consisting of two parallel plates having convex rearward edges and provided with bearings lying in seats in lug-plates 115 parallel with the central plate, shoes having concave faces bearing upon the convex edges of the tumblers and provided with openings which are expanded upon opposite sides, and spiral springs impelling said shoes and coiled 120 upon spindles straddled by the tumblers and supported by a T-plate at one end and a cross-head at the other, substantially as described.

In testimony whereof I have affixed my signature in presence of two witnesses.

HARRY COMSTOCK.
